(57) **CLAIM**

The ornamental design for the media disc storage container, as shown and described.

DESCRIPTION

FIG. 1 is a perspective view of a media disc storage container in an open configuration;

FIG. 2 is a perspective view of the media disc storage container of FIG. 1 in a closed configuration;

FIG. 3 is a front elevation of FIG. 1;

FIG. 4 is a rear elevation of FIG. 1;

FIG. 5 is a left side view of FIG. 3;

FIG. 6 is a right side view of FIG. 3;

FIG. 7 is a top plan view of FIG. 3; and,

FIG. 8 is a bottom plan view of FIG. 3.

The broken lines form no part of the claimed design.
